Albert J. Friske
ATTY

UNITED STATES PATENT OFFICE.

ANNA PICHOWETZ BRAND, OF CHICAGO, ILLINOIS, ASSIGNOR TO BENJAMIN A. BRAND, OF CHICAGO, ILLINOIS.

GARTER AND ARM BAND.

Application filed April 7, 1924. Serial No. 704,871.

To all whom it may concern:

Be it known that I, ANNA PICHOWETZ BRAND, a citizen of the United States, residing at Chicago, in the county of Cook and State of Illinois, have invented certain new and useful Improvements in Garter and Arm Bands; and I do hereby declare the following to be a full, clear, and exact description of the invention, such as will enable others skilled in the art to which it appertains to make and use the same.

This invention relates to improvements in garters and arm bands, and has for one of its principal objects the provision of a garter or arm band which, while being elastic, shall at the same time be free from the disadvantages ordinarily present in the usual form of woven elastic material now on the market, and which will, moreover, be entirely serviceable and dependable.

One of the important objects of this invention is the provision of a garter or arm band composed of a suitable elastic material such as cloth tape or the like, whereby any stretching of the rubber near to or beyond its elastic limit will be effectively prevented while at the same time all ordinary stretching to which the garter or arm band will be put in use will be allowed.

Another important object of this invention is the provision of an elastic member for garters, belts, arm bands, or similar objects, which shall preferably be composed of a tube of rubber or the like having therein and extending therethrough a strip of nonelastic material which will be suitably fastened at its ends to the end supports of the tube, which strip of nonelastic material is of a length greater than the normal length of the rubber tube and of such a relation to the length of the rubber tube that any excessive stretching of said rubber tube will be effectively prevented.

Still another and further important object of this invention is the provision in a garter or arm band of an elastic member supplemented by a nonelastic member of greater normal length and secured in cooperative relation thereto by means of rows of extensible stitches.

Other and further important objects of the invention will be apparent from the disclosures in the accompanying drawings and following specification.

The invention, in a preferred form, is 55 illustrated in the drawings and hereinafter more fully described.

In the drawings:

Figure 1 is a front elevation of a garter constructed in accordance with the improved 60 principles of this invention, parts being broken away.

Figure 2 is a front elevation of a novel arm band as contemplated by the present invention, portions being likewise broken 65 away.

As shown in the drawings:

The reference numeral 10 indicates generally the cloth portion or nonelastic base member of an ordinary garter or the like 70 being of preferably triangular form and having attached at the lower end thereof an ordinary hose gripping element as illustrated at 12.

Adapted to co-operate with the member 75 10 at the upper corners thereof is the elastic member of this invention, comprising essentially a tube of pure rubber as best illustrated at 14, and having passing therethrough a tape or the like 16 which is of a 80 greater length than the normal length of the rubber tube 14.

As illustrated, the edges of the rubber tubing 14 are reenforced or joined together by means of suitable stitching or the like as 85 18, which stitching is of such a design and is applied to the tubing 14 in such a manner that the stitching itself will be capable of longitudinal extension along its line of stretch and without any danger 90 or possibility of tearing the tubing in such stretching action or of hindering the stretching action in any way. It will be obvious that this garter can be applied without the use or necessity of any auxiliary attaching 95 elements such as buckles or the like.

Figure 2 illustrates an arm band constructed along practically the same lines as the garter illustrated in Figure 1, but which obviously is not provided with a hose supporting element, but merely comprises a circular band composed of a piece of rubber tubing precisely similar to that illustrated in Figure 1 and, as illustrated by the broken away portions, the tube 14 has passing 100 through the interior thereof a nonelastic non-stretchable element 16 in the form of a piece of tape which may be of any suitable

material. For purposes of better illustration the greater portions of the tube 14 are shown as broken away, illustrating the condition of the tape 16 when the same is in normal position in the unstretched tubing 14. However, it will be obvious that when the tubing is stretched the tape 16 will act to prevent any undue extension thereof, which extension might otherwise go beyond its elastic limit causing breakage and consequent annoyance.

Lines of stitching 18 extend around the peripheries of the arm band as illustrated in Figure 2, which lines of stitching are similar to those illustrated in the garter of Figure 1, and which act in precisely the same manner, namely, adapting themselves to variations in the circumference or extent of the arm band or garter as occasioned by the uses to which they are put by the wearer. The lines of stitching 18 serve to reenforce the edges of the tubing 14 and may also be employed to actually maintain the rubber in tubular form if the same is composed of a bent-over strip of rubber. The construction is such as to be easily kept clean, being readily washed, and moreover will greatly outwear the ordinary garter or arm band on account of the elimination of woven semi-elastic elements. It will be obvious that two or more parallel lengths of tubing 14 may be employed in a belt, garter, or arm

band instead of the single elements illustrated if more security or greater supporting qualities are desired.

35

I am aware that many changes may be made and numerous details of construction varied throughout a wide range without departing from the principles of this invention, and I therefore do not purpose limiting the patent granted hereon otherwise than as necessitated by the prior art.

40

I claim as my invention:

1. In a supporter, a limb encircling tube formed of opposed separate sections of flat and longitudinally elastic material, a non-elastic flat tape extending longitudinally within said tube and of a greater length than the normal length of the tube, and means joining the opposed tube sections along the longitudinal edges thereof and serving to retain said sections in flat opposed relation throughout.

45

2. In a supporter, a limb encircling tube formed of opposed sections of flat and longitudinally elastic material, a non-elastic flat tape extending longitudinally within said tube and of a length greater than the normal length of the tube, and a series of connected elastic stitches joining the opposed tube sections along the longitudinal edges thereof.

50

In testimony whereof I affix my signature.

ANNA PICHOWETZ BRAND.
